UNITED STATES PATENT OFFICE.

AB C. SMITH, OF WARREN, ARKANSAS.

CABLE-CLAMP.

1,092,668.

Specification of Letters Patent.

Patented Apr. 7, 1914.

Application filed April 7, 1913. Serial No. 759,487.

To all whom it may concern:

Be it known that I, AB C. SMITH, a citizen of the United States, and residing at Warren, in the county of Bradley and State of Arkansas, have invented certain new and useful Improvements in Cable-Clamps, of which the following is a specification.

This invention relates to improvements in cable clamps.

10 An object of the device is to provide a means for securely clamping a cable therein and one in which the clamp which is simple and inexpensive to manufacture may be readily applied to and detached from the 15 cable in use.

A further object of the invention is to provide such a clamp which by an inversion of an element thereof and its disengagement thereby from its other element may be 20 changed in the size of its receiving socket and so as to accommodate and clamp different diameters of cables.

With these general objects in view and others that will appear as the nature of the 25 invention is better understood, the same consists of the novel combination and arrangement of parts as hereinafter more fully described, illustrated in the accompanying drawings, and pointed out in the appended 30 claims.

In the drawings forming a part of this application and in which like reference numerals designate corresponding parts throughout the several views:—Figure 1 is 35 a side elevation of the clamp positioned upon a cable, the latter shown in dotted lines, Fig. 2 is a vertical transverse sectional view thereof taken upon line 2—2 of Fig. 1, and Figs. 3 and 4 are perspective views respectively of the upper and lower clamp members.

Referring more in detail to the drawings, the main or what may be termed base member 10 of the clamp is provided with a supplemental top or what may be termed cover member 11 removably hinged thereto and adjustably retained and locked thereon by bolt members 12.

At one end of the base member projecting posts 13 are provided with open end sockets 14 and have their inner top faces curved as at 15. The opposite end of said face member is provided with a threaded bore 16 upon each side thereof which bores 55 are within side projections 17 between which and the posts 13 which also project laterally

are the intermediate grooved sides or sockets 18. Said threaded bores 16 are extended through hollow integral posts 19 upon said base member, the latter extending to a height intermediate that of the post 13 while said continuous bores may be internally screw-threaded their entire or a portion of their length. The cover member 11 adjacent one end is provided with laterally-extending lugs 20 having their inner faces thereof curved and adapted to seat within the sockets 14 of the base member and thereby to hinge the cover 11 thereto, it being evident that a movement of the cover relative to the base member allows the shoulder 21 of said cover to move upwardly substantially adjacent to said curved surface 15 and also effecting a disengagement of the lugs 20 from the sockets 14 to effect a separation of the base 70 and cover members. Forwardly of said cover 11 the same is provided with slightly oblong-shaped openings 22 having smooth interiors and adapted to receive the tubular posts 19 and to fit thereover upon a closing 80 of the members together, the same being in hinged relation above noted. It is apparent that a cable member 23 when placed within the semi-circular socket 24 of the base member will also be received within the corresponding socket 25 of the cover member and that upon a tightening of the bolts 12, the cable will thus be firmly clamped between said members and within the clamp, the manipulation of the bolts being effected 90 through the squared heads 26 thereof provided with wrench-hold surfaces and lever-receiving openings 27 if desired which heads contact the upper surface of the cover member to draw the same closely upon the 95 cable by screwing home the bolts 12.

The opposite faces of the cover member 11 are provided with sockets of different radii, the top socket 28 as illustrated herein being of a less radius than that of said socket 25. This provision is for the purpose of accommodating different sized cables within the clamp, the cover having the two sized sockets, and the base having a single socket. As shown in Figs. 1 and 2, the positioning of the cover member 11 upon the base member 10 with the socket 25 lowermost, brings the socket 25 of the cover above the socket 24 of the base so that said sockets coöperate to provide a bore of the greatest 110 diameter of which the device is capable. Longitudinal marginal shoulders 29 are pro-

vided at opposite sides and at the top of the base socket 24 and upon said shoulders is adapted to rest the projecting portion 31 of the cover, which contains the socket 28 when 5 the cover is positioned in its inverted position from that shown in Figs. 1 and 2. The present illustrated position in Fig. 2 accommodates the cable of greatest diameter while the position of the same with the cover inverted will hold a cable of a less diameter.

10 It is obvious that many uses may be made for the present cable clamp which is adaptable not only to use in connection with well drilling operations as well as any other 15 many cases where it is desirable to forcibly hold or draw cable or similar member.

16 While the forms of the invention herein shown and described are what are believed to be preferable embodiments thereof, it is 20 nevertheless to be understood that minor changes may be made in form, proportion, and details of construction without departing from the spirit and scope of the invention as set forth in the appended claims.

25 Having thus fully described the invention and in what manner the same is designed for use, what I claim as new and desire to secure by Letters Patent of the United States is:—

1. A cable clamp comprising a base member, side socketed posts projecting from one 30 end thereof, a cover member, lugs upon one end of said cover member and adapted to engage the sockets of said posts, hollow posts mounted upon the opposite end of said base member and in alinement with threaded 35 bores through said base member, adjustable locking means positioned within said bores, and said body and cover members having coöperating sockets adapted to engage a 40 cable.

2. A cable clamp comprising a base member, side socketed posts projecting from one end thereof, a cover member, lugs upon one end of said cover member and adapted to engage the sockets of said posts, hollow 45 posts mounted upon the opposite end of said base member and in alinement with threaded bores through said base member, adjustable locking means positioned within said bores, said base member provided with a longitudinal 50 groove in the top thereof, said cover member provided with opposite longitudinal grooves of different diameters centrally positioned therein, said cover member adapted to be positioned with either of 55 its faces adjacent the base member for bringing either of the grooves of said cover in co-operative relation with the groove of said base.

3. A cable clamp comprising a base member, a cover removably hinged thereto, locking means for said base and cover, said base member provided with a central longitudinal socket in one face thereof, longitudinal marginal shoulders at opposite sides of the 60 top of said socket, one face of said cover provided with an extension adapted to be received upon said marginal shoulders and having a longitudinal socket therein of the same diameter as said base socket and the 65 opposite side of said cover provided with a longitudinal socket of a diameter greater than that of the other sockets.

In testimony whereof I affix my signature in presence of two witnesses.

AB C. SMITH.
